(57) **CLAIM**

The ornamental design for a folding material sheet with perforation pattern, as shown and described.

DESCRIPTION

FIG. 1 is a plan view of a folding material sheet with perforation pattern;

FIG. 2 is a plan view of enlarged detail area 2 circumscribed within FIG. 1; and,

FIG. 3 is a perspective view of the folding material sheet with perforation pattern of FIG. 1 folded along the perforation pattern.

The evenly spaced broken lines surrounding FIGS. 1 and 3 depict the boundaries of the claim and form no part thereof. The dot dash dot broken lines within FIG. 1 and surrounding FIG. 2 denote the boundaries of the detail area and form no part of the claimed design.
